CONVERSION OF SULFUR CONTAINING HYDROCARBONS

Henry W. Grote, Downers Grove, Ill., assignor to
 Universal Oil Products Company, Chicago, Ill.,
 a corporation of Delaware

Application December 28, 1946, Serial No. 718,930

4 Claims. (Cl. 196—50)

1

This invention relates to the conversion of hydrocarbons. It is more particularly concerned with a combination desulfurization-cracking process in which a high-boiling hydrocarbon is desulfurized and is then converted to lower-boiling hydrocarbons in the presence of a single cracking catalyst.

It is generally recognized that the availability of low-sulfur crudes is diminishing, which fact forces refiners to process higher sulfur crudes. The result is that the average over-all sulfur content of the crudes being processed is constantly increasing. Crudes of this nature are relatively undesirable because the sulfur compounds present therein not only are odiferous, but because they are also corrosive and, in the case of gasoline, detrimentally affect the susceptibility to the addition of tetraethyl lead. It has been found that the fractions of such crudes that boil above the gasoline range are relatively poor catalytic cracking charge stocks because, in general, they give lower yields of gasoline at a given conversion and because the gasolines produced therefrom at the usual high temperature cracking conditions contain very appreciable amounts of stable sulfur compounds. The sulfur contents of gasolines produced from such charging stocks appears to be a function of the amount of sulfur in the charge and a function of the olefin content of the gasoline. That is, the more unsaturated the gasoline the higher the sulfur content. This relationship apparently is due to the fact that hydrogen sulfide is the initial product formed from the decomposition of the original sulfur compounds in the feed stock, and this hydrogen sulfide then combines in part with the olefins produced by the cracking reaction to form stable sulfur compounds that boil in the gasoline range. Therefore, it can be seen that it would be advantageous to remove most of the sulfur from the feed to the catalytic cracking unit and to remove the sulfur in such a manner that substantially no olefins are present when the hydrogen sulfide is present. I have invented such a process.

In one embodiment my invention relates to a combination desulfurization-cracking process which comprises supplying solid cracking catalyst and a sulfur-containing hydrocarbon to a desulfurization zone at a temperature and pressure and for a time sufficient to effect at least partial desulfurization of said hydrocarbon, supplying the desulfurized hydrocarbon and another portion of the solid cracking catalyst to a cracking zone maintained at cracking conditions, com-

2

mingling the catalyst from the desulfurization zone with said other portion of catalyst, subjecting the commingled catalyst to stripping to remove at least a portion of the hydrocarbons adsorbed thereon, and regenerating the stripped catalyst.

In a more specific embodiment my invention relates to a combination cracking and desulfurization process which comprises subjecting a sulfur-containing hydrocarbon to the action of a solid cracking catalyst at a temperature of from about 650 to about 850° F. to convert at least a portion of the sulfur compounds in said hydrocarbon to hydrogen sulfide, separating the hydrocarbon and the hydrogen sulfide from the catalyst, separating the hydrogen sulfide from the bulk of the hydrocarbon, commingling the catalyst from the desulfurization step with another portion of the solid cracking catalyst, subjecting the last named hydrocarbon to the action of the commingled catalysts at cracking conditions, separating the catalyst from the cracked products, subjecting the catalyst to stripping to remove at least a portion of the hydrocarbons adsorbed thereon, and regenerating the stripped catalyst.

Desulfurization of hydrocarbons occurs more completely at a somewhat lower temperature level than in the 850°—1100° F. range used in the catalytic cracking of hydrocarbons. In the present process I use a separate desulfurization reactor which operates in the approximate temperature range of 650 to 850° F. or just slightly above the dew point of the hydrocarbon fed to this reactor. At this temperature level, adsorption of heavy hydrocarbons on the catalyst occurs to an appreciable extent, and if spent catalysts from the desulfurization reactor were taken directly via a stripper to the regenerator where the hydrocarbon and carbonaceous deposits were removed therefrom by combustion, the efficiency of stripping would be low because of the low stripping temperature. Consequently, a considerable amount of hydrocarbon material would be burned from the catalyst in the regenerator. This would be undesirable not only because of the loss of hydrocarbon but because of the increased oxygen requirements, etc., in the regeneration step.

One of the features of this invention is the raising of the temperature of the spent catalyst from the desulfurization reactor to a point at which said catalyst can be more efficiently stripped and more adsorbed hydrocarbons removed therefrom before the catalyst is passed to the regenerator. One method of accomplishing this in the process of my invention is to pass the catalyst from the

desulfurization reactor to the cracking reactor where the used desulfurization catalyst is intimately mixed with and heated by the hot cracking catalyst in the cracking reactor. The commingled stream of hot catalyst from the cracking reactor is then passed to a single stripper and then to the regeneration zone. An alternative method of raising the temperature of the used desulfurization catalyst is to commingle said catalyst with the hot used cracking catalyst that is being charged to the stripper.

It can be seen from the description of my process thus far given, that I accomplish desulfurization and cracking in separate zones with a single catalytic material employing a single stripper and producing a gasoline substantially uncontaminated with sulfur compounds. Other advantages and features of this process will be apparent from the following detailed description of the attached flow diagram which illustrates one method by which the objects of the present invention may be accomplished.

Referring to the diagram, a 30° A. P. I. gas oil of boiling range 437-739° F. containing 1.76 weight per cent sulfur, is charged through line 1 containing valve 2 and picks up regenerated catalyst from regenerator 3 which passes through line 4 containing valve 5. The mixture of hydrocarbon and catalyst passes upwardly through line 1 into desulfurization reactor 6. The temperature of the raw oil feed is adjusted to give a temperature within reactor 6 of from about 650 to about 850° F. and preferably from 700 to 800° F. Any suitable metal oxide cracking catalyst may be employed such as silica-alumina, silica-zirconia, silica-alumina-zirconia, silica-magnesia, silica-alumina-magnesia, and the like. These catalysts may be prepared in any suitable manner including separate, successive, and coprecipitation methods. In some cases naturally occurring materials such as Filtrol, Super Filtrol, acid-treated montmorillonite, etc., may be employed. The preferred catalysts are synthetic composites comprising silica-zirconia, silica-alumina, silica-alumina-zirconia and silica magnesia because these catalysts are less detrimentally affected by sulfur than the others. For the purposes of this description it will be assumed that the catalyst is fluidizable, i. e., it is in a finely divided state such as a powder or microspheres. However, it will be readily apparent as the description proceeds that my process is not limited to fluid-type operation but that the moving bed technique also may be employed in this process.

A dense phase bed of solid catalyst is maintained within desulfurization reactor 6 and is kept in a fluid-like state of relatively high density by the hydrocarbons passing therethrough at a velocity which partially counteracts the force of gravity on the solid particles and brings about their hindered settling within the bed. Above the dense phase bed is a relatively light phase region having reduced catalyst density. At least a portion of the sulfur compounds in the charging stock are converted to hydrogen sulfide and the conversion products are passed through separation means such as a cyclone separator in the upper portion of reactor 6 wherein entrained catalyst particles are removed from said conversion products and returned to the dense phase. The conversion products are then discharged into line 7 containing valve 8 and are passed to suitable separation means 9 which in this illustration is a distillation column.

Column 9 may be a simple stripper wherein hydrogen sulfide is removed from the hydrocarbons and discharged through line 10 containing valve 11. On the other hand, if there has been some conversion of the high-boiling hydrocarbons to gasoline in desulfurization reactor 6, the gasoline and the hydrogen sulfide may be separated from the unconverted gas oil in distillation column 9 and a subsequent separation effected between the gasoline and the hydrogen sulfide. Such gasoline as is produced in reactor 6 is relatively saturated because of the low temperature and low conversion prevailing there.

The hydrogen sulfide-free hydrocarbon from column 9, which has a sulfur content of 0.30% is removed through line 12 containing pump 13 and valve 14 and is commingled with a stream of hot regenerated catalyst from regenerator 3, said stream of catalyst being supplied through line 15 containing valve 16. The mixture of catalyst and oil is directed into the lower portion of cracking reactor 17 and is substantially uniformly distributed over the cross sectional area of the reactor by means such as perforated plates or grids horizontally disposed therein. A dense phase bed of solid catalyst particles is maintained in cracking reactor 17. The temperature in said reactor is maintained within the range of 850 to 1100° F. and preferably between 900 and 975° F. The temperature is maintained by the heat supplied thereto in the hot regenerated catalyst, but if necessary the hydrocarbon charged to the cracking reactor may be preheated. In the reactor a portion of the high-boiling hydrocarbons are converted to lower-boiling hydrocarbons and the conversion products are directed from reactor 17 through line 18 containing valve 19 and into distillation means 20, which may comprise one or more fractionators and absorbers, wherein separation is effected between the gas, gasoline, and recycle stock. For the purpose of this description, gaseous hydrocarbons are withdrawn through line 21 containing valve 22, gasoline is withdrawn through line 23 containing valve 24, and recycle stock is withdrawn through line 25 containing pump 26 and valve 27. If desired, a portion or all of the recycle stock may be passed back to cracking reactor 17 through line 28 containing valve 29.

In some instances, particularly when the cracking operation is conducted to yield a relatively saturated gasoline, it may be desirable to use a common fractionator for the effluent streams from both reactors. In such a case the hydrocarbon effluent from desulfurization reactor 6 is passed through line 7 and into line 30 containing valve 31 and thence into line 18 and into distillation means 20.

Used catalyst from desulfurization reactor 6 may be withdrawn through line 32 containing valve 33 and passed into cracking reactor 17 where it commingles with and is heated by the hot cracking catalyst. The catalyst will flow from reactor 6 to reactor 17 without the aid of a carrier fluid if the transfer line is inclined at an angle greater than the angle of natural repose of the catalyst particles. However, if desired, the catalyst may be transported between the reactors by means of a carrier fluid. Used desulfurization catalyst may enter reactor 17 at any point, however, the point selected usually is in the region of the dense phase catalyst zone within said reactor. If desired, the catalyst from reactor 6 may be mixed with the hot regenerated catalyst in line 12. This procedure results in a substan-

tially uniform catalyst temperature within the cracking reactor. At times, it is advantageous to have the used desulfurization catalyst entry point near the top of the dense catalyst phase within reactor 17. This creates a relatively cooler catalyst zone above a hotter catalyst zone. The higher-boiling hydrocarbons are converted to lower-boiling hydrocarbons in the hotter zone, and said lower-boiling hydrocarbons are then treated in the cooler zone. The treating step tends to lower the olefin content of the gasoline thus making a more saturated product.

The mixture of used catalysts in reactor 17 is withdrawn through line 34 and passed into stripper 35. A suitable stripping medium such as steam or other inert gas or vapor is passed into stripper 35 near the bottom through line 36 containing valve 37 and rises therethrough countercurrently to the descending catalyst therein. The upper portion of stripper 35 provides a separating or disengaging space for vapors and catalyst particles. Suitable plates and grids may be placed within stripper 35 to provide thorough contact between the countercurrently moving streams. The hydrocarbons desorbed from the catalyst and the stripping medium pass from chamber 35 through line 45 and valve 46 into the upper portion of reaction chamber 17 where they combine with the conversion products and are discharged therewith. In some instances, it may be desirable to pass the used desulfurization catalyst from reactor 6 directly into line 34 via line 32 and line 38 containing valve 39.

The stripped catalyst is passed from stripper 35 through line 40 into regenerator 3 wherein it is contacted with an oxygen-containing gas at a combustion temperature, and the combustible material is burned therefrom. The oxygen-containing gas is supplied to the regenerator through line 41 containing valve 42 and the combustion products are removed from the regeneration zone through line 43 containing valve 44.

I claim as my invention:

1. A combination desulfurization - cracking process which comprises supplying solid cracking catalyst and a sulfur-containing hydrocarbon to a desulfurization zone at a temperature and pressure and for a time sufficient to effect at least a partial desulfurization of said hydrocarbon, supplying desulfurized hydrocarbon and another portion of the solid cracking catalyst to a cracking zone maintained at cracking conditions; withdrawing catalyst from said desulfurization zone and introducing said withdrawn catalyst into said cracking zone, withdrawing catalyst from said cracking zone and subjecting the latter catalyst to stripping and regeneration, and supplying one portion of regenerated catalyst to desulfurization zone and another portion to the cracking zone as aforesaid.

2. A combination desulfurization - cracking process which comprises supplying solid cracking catalyst and a sulfur-containing hydrocarbon

5 to a desulfurization zone at a temperature of from about 650 to about 850° F., supplying desulfurized hydrocarbon and another portion of the solid cracking catalyst to a cracking zone maintained at a temperature of from about 850 to about 1100° F.; withdrawing catalyst from said desulfurization zone and introducing said withdrawn catalyst into said cracking zone, withdrawing catalyst from said cracking zone and subjecting the latter catalyst to stripping and regeneration, and supplying one portion of regenerated catalyst to desulfurization zone and another portion to the cracking zone as aforesaid.

15 3. A combination desulfurization - cracking process which comprises supplying solid cracking catalyst and a sulfur-containing hydrocarbon to a desulfurization zone at a temperature and pressure and for a time sufficient to convert at least a portion of the sulfur compounds in said hydrocarbon to hydrogen sulfide, separating the hydrocarbon and the hydrogen sulfide from the catalyst, separating the hydrogen sulfide from the bulk of the hydrocarbon, subjecting the last 20 named hydrocarbon to the action of another portion of a solid cracking catalyst at cracking conditions; withdrawing catalyst from said desulfurization zone and introducing said withdrawn catalyst into said cracking zone, withdrawing catalyst from said cracking zone and subjecting the latter catalyst to stripping and regeneration, and supplying one portion of regenerated catalyst to desulfurization zone and another portion to the cracking zone as aforesaid.

25 35 4. A combination desulfurization - cracking process which comprises supplying solid cracking catalyst and a sulfur-containing hydrocarbon to a desulfurization zone at a temperature of from about 650 to about 850° F. to convert at least a portion of the sulfur compounds in said hydrocarbon to hydrogen sulfide, supplying desulfurized hydrocarbon and another portion of the solid cracking catalyst to a cracking zone maintained at a temperature of from about 850 to about 1100° F.; withdrawing catalyst from said desulfurization zone and introducing said withdrawn catalyst into said cracking zone, withdrawing catalyst from said cracking zone and subjecting the latter catalyst to stripping and regeneration, and supplying one portion of regenerated catalyst to desulfurization zone and another portion to the cracking zone as aforesaid.
